UNITED STATES PATENT OFFICE.

JULIUS BÖRSUM, OF LILLEHAMMER, NORWAY.

THRESHING-MACHINE.

SPECIFICATION forming part of Letters Patent No. 606,503, dated June 28, 1898.

Application filed October 30, 1897. Serial No. 656,946. (No model.)

To all whom it may concern:

Be it known that I, JULIUS BÖRSUM, mechanical engineer, of Lillehammer, Norway, have invented certain new and useful Improvements in Threshing-Machines; and I do hereby declare that the following is a full, clear, and exact description of the same.

My invention relates to threshing-machines; and it consists in certain new arrangements whereby the straw and grain are in a more complete manner separated from each other after having been loosened by the threshing-drum and before they have reached the straw-shakers.

The objects of my invention are to simplify the construction of threshing-machines, to limit the size of the machine, and to diminish the power necessary for driving the same. To this end my invention consists in arrangements hereinafter specified and claimed.

Annexed drawing shows a longitudinal vertical section through the upper part of a threshing-machine, in which—

A indicates the straw-shakers, and B C D the mechanism for imparting rocking motion to the same. As my invention does not relate to these parts, which are of well-known construction, the same need no further explanation, being only shown to make the description of the parts of invention more plain and clear.

F is the feed-board, at the end of which is arranged the threshing-drum G. This drum may be provided with beaters or pegs or be of any other suitable construction. It is surrounded by a shell H in such manner that the threshing drum or cylinder will throw the threshed-out grain and straw forward in a substantially horizontal direction. From the forward end of the shell H extends a deflecting-shell I, whose upper wall is substantially horizontal for a certain distance and then curves downward and backward to, or approximately to, the straw-shaker A, which is inclosed by said shell except at its delivery

end, whereby the threshed-out grain is deflected and guided forwardly and then downwardly to the receiving end of the shaker, where it falls into a hopper and thence into any suitable receiver.

In view of the great specific gravity of the grain relatively to the straw and lighter particles, as the chaff, said grain under the action of the threshing-cylinder acquires a greater momentum than the lighter materials and is projected farther toward or to the receiving end of the shaker, where it is deflected downwardly by the curved end of the shell I onto the straw-shaker and is rapidly screened. The straw and chaff being lighter, and hence having less momentum, their flight toward the receiving end being, furthermore, checked in a measure by the resistance of the air above the shaker A within the shell, fall nearer to the delivery end of the shaker and are rapidly discharged from the machine free from grain. In this way there is arranged a very effective assorting of grain and straw before the straw reaches the straw-shakers, and for this reason the length of the said straw-shakers may be reduced to about half the length necessary in machines where the threshed material is led straight down to the straw-shakers.

I claim—

In a threshing-machine, the combination of the feed-board the overshot threshing-cylinder, the concave, the semicylindrical deflecting-shell H, curved deflecting-shell I, beneath the feed-board, and the upwardly-inclined straw-shaker A adapted to move the straw out of the machine in a direction the reverse of that in which it is projected into said shell I by the cylinder, for the purpose set forth.

In witness whereof I have hereunto set my hand in presence of two witnesses.

JULIUS BÖRSUM.
